JUICE HEATING UNIT

George H. Tay, Philipsburg, Pa., assignor to Lee
Metal Products Company, Inc., Philipsburg,
Pa.

Application June 22, 1938, Serial No. 215,239

7 Claims. (Cl. 257—207)

This invention is an improvement upon the heating apparatus disclosed in my U. S. Patent 2,087,363 July 20, 1937, and relates generally to apparatus for applying heat to liquids.

5 The primary object of the present invention is to provide a heating unit adapted to be detachably connected to the bottom of a tank, as a substitute for the coils commonly used in such tanks for the cooking of juices, such as tomato juice.

10 Coils commonly used for the cooking of juices become caked with solids deposited from the juices after comparatively short periods of use; and it becomes necessary to remove the coils periodically from the tanks to clean them. In many cases, this deposit on the coils is caused by the condensation of steam in the lower parts of a heating coil. Where such condensation occurs, there is a lowering of temperature which 15 causes the juice in contact with the cooler parts of the coils to cake thereon. These deposits act somewhat as a heat insulator, and increase the rate of deposit until the whole coil becomes caked and practically useless until the deposits 20 shall have been removed therefrom.

25 A further object of the present invention, therefore, is to provide a juice heating unit in which the heating elements are constructed to prevent the caking of solids on any part thereof, and which can be readily cleaned, when necessary, without removal of the unit from the tank.

30 Another object of the invention is to provide a juice heating unit of the character referred to which can be manufactured as a separate unit adapted to be connected detachably to the bottom of any ordinary tank.

35 Other objects of the invention will become apparent as the detailed description thereof provides.

40 In the drawing:

Figure 1 is a central vertical section of a heating unit constructed in accordance with this invention, and illustrated as applied to the 45 bottom of a tank; and

Figure 2 is a horizontal section taken on the line 2—2 of Figure 1.

45 As shown in the drawing, the heating unit comprises a tubular ring 3, connected at diametrically opposite sides to an inner cylinder 4 and an outside cylinder 5. These cylinders and tubular ring are coaxial, and the space between the lower edges of the cylinders is closed by a flat bottom ring 6.

50 The tubular ring 3 and the flat bottom ring 6

are welded, or otherwise secured, to the inside and outside cylinders 4 and 5 to form a steam tight chamber. Holes 7 are drilled at intervals through the bottom of the tubular ring 3 to permit the passage of steam from the tube into the 5 annular chamber formed by the coaxial cylinders 4 and 5. A pipe 8, connected at its lower end to a source of supply of steam, is passed through an aperture 9 in the bottom ring 6 and across the chamber formed by the cylinders 4 10 and 5 to an aperture 10 formed in the tubular ring 3 to receive with steam tight fit the upper end of said pipe 8.

The cylinders 4 and 5 are preferably corrugated; and have their corrugation arranged perpendicular to the axis of the unit. The lower edges of both cylinders are cut wider on the sides thereof diametrically opposite to the steam pipe 8 in order to allow for drainage of condensates from the chamber. A drainage pipe 20 15 11 is welded, or otherwise suitably secured, to the flat bottom ring 6 at the lowest point thereof so as to ensure complete drainage of the condensates.

The cylinders may be plain or corrugated, according to the metal employed in their construction, or the pressure which they are required to withstand. Preferably, they are corrugated; and the corrugations are formed parallel to each other to strengthen the walls of the chamber 30 by the coaxial cylinders. Steel rings 12 may be seated in any desired number of these corrugations within the chamber to add to the strength of the walls thereof and may be permanently secured by welding or otherwise to 35 said walls. In addition to strengthening the walls of the chamber, these rings 12 break up or prevent streams of water or condensation forming on the said cylinders.

The lower ends of the pipes 8 and 11 are 40 provided with flanges 13 and 14, respectively adapted to seat on the bottom of a tank 16 provided with apertures through which said pipes project. The projecting ends of said pipes beyond the flanges 13 and 14 are screw threaded 45 to receive the nuts 15 and 16, respectively which may be adjusted against the bottom of the tank to clamp the heating unit securely in operative position. The tank 16 may be provided with the usual valve controlled drain pipe 17.

50 It will be obvious from inspection of the drawing that the heating unit may be applied to and removed bodily from the tank 16 or any other tank adapted for the reception of such unit. It will also be obvious that the cleaning 55

of both inner and outer surfaces of the unit can be readily effected by running a swab around all the exposed surfaces, while the unit is maintained in position in the tank.

5. What I claim is:

1. A heating unit adapted to be detachably connected to the bottom of a tank and comprising: two coaxial sheet metal cylinders spaced apart radially, a circular tube secured to the top edges of each of said cylinders, a ring secured to the bottom edges of said cylinders, said tube and ring forming with said cylinders a closed annular heating chamber, said tube being provided with apertures communicating with said chamber, means for conducting heating fluid to said tube, and means connected to said ring for draining said chamber.
2. A heating unit adapted to be detachably connected to the bottom of a tank and comprising: two coaxial sheet metal cylinders spaced apart radially, a circular tube secured to the top edges of each of said cylinders, a ring secured to the bottom edges of said cylinders, said tube and ring forming with said cylinders a closed annular heating chamber, one side of said chamber being longer than the diametrically opposite side, means for conducting a heating fluid to said tube at the top of the shorter side of said chamber, and draining means connected to said ring at the bottom of the longer side of said chamber.
3. A heating unit adapted to be detachably connected to the bottom of a tank and comprising: two coaxial sheet metal cylinders spaced apart radially, a circular tube secured to the top edges of each of said cylinders, a ring secured to the bottom edges of said cylinders, said tube and ring forming with said cylinders a closed annular heating chamber, one side of said chamber being longer than the diametrically opposite side, a pipe extending through said ring and across said chamber into communication with said tube at the top of said shorter side, and a drain pipe connected to said ring at the longer side of said chamber.
4. A heating unit adapted to be detachably connected to the bottom of a tank and comprising: two coaxial sheet metal cylinders spaced apart radially and closed at the top and bottom edges to form a closed annular chamber, means for heating said chamber, the walls of said cyl-

inders being provided with corrugations substantially perpendicular to the axis of said chamber, and means on the corrugations within said chamber to interrupt the downward flow of condensates on said walls.

5. A heating unit adapted to be detachably connected to the bottom of a tank and comprising: two coaxial sheet metal cylinders spaced apart radially and closed at the top and bottom edges to form a closed annular heating chamber, means for conducting heating fluid to the top of said chamber, means for conducting condensates of said fluid from the bottom of said chamber, said cylinders being provided with corrugations substantially perpendicular to the axis of said chamber, and stiffening rings seated in corrugations of the cylinders within said chamber.
- 10

6. A heating unit adapted to be detachably connected to the bottom of said tank and comprising: two coaxial sheet metal cylinders spaced apart radially and closed at the top and bottom edges to form a closed annular heating chamber, means for conducting heating fluid to the top of said chamber, means for conducting condensates of said fluid from the bottom of said chamber, said cylinders being provided with corrugations substantially perpendicular to the axis of said chamber, and stiffening rings seated in corrugations of the cylinders within said chamber, said stiffening rings being circular in cross-section and projecting into said chamber from the opposed surfaces thereof to form means for interrupting the downward flow of water of condensation.

- 20
  - 25
  - 30
  - 35
  - 40
  - 45
  - 50
7. In apparatus for heating liquids, a tank, a heating unit comprising: two coaxial sheet metal cylinders spaced apart radially, a circular tube secured to the top edges of each of said cylinders, a ring secured to the bottom edges of said cylinders, said tube and ring forming with said cylinders a closed annular heating chamber, one side of said chamber being longer than the diametrically opposite side, a pipe extending across the shorter side of said chamber into communication with said tube at the top of said shorter side for conducting heating fluid to said tube, a drain pipe extending through said ring at the longer side of said chamber, and means for detachably securing said pipes to a support.
